DESIGN FOR A COMBINED SOUND AND
MOTION-PICTURE PROJECTOR AND
CARRYING CASE THEREFOROsmond Kendall, Ottawa, and Smiley W. Loach,
Toronto, Ontario, Canada, assignors to Raymond Allen, Toronto, Ontario, Canada

Application February 26, 1947, Serial No. 137,190

Term of patent 14 years

(Cl. D61—1)

To all whom it may concern:

Be it known that we, Osmond Kendall and Smiley W. Loach, both citizens of Canada, residing at the city of Ottawa, county of Carleton, Province of Ontario, Dominion of Canada, and the city of Toronto, Province of Ontario, county of York, Dominion of Canada, respectively, have invented a new, original, and ornamental Design for Combined Sound and Motion-Picture Projector and Carrying Case Therefor, of which the following is a specification, reference being had to the accompanying drawings, forming part thereof.

In the drawings:

Figs. 1, 2, 3, 4, and 5 are, respectively, a front elevational view, a right end elevational view, a left end elevational view, a top plan view, and a rear elevational view of a combined sound and motion-picture projector and carrying case there-

for in a closed condition, showing our new design; and Fig. 6 is a perspective view of the same in an open or operative condition.

We claim:

The ornamental design for a combined sound and motion-picture projector and carrying case therefor, as shown.

OSMOND KENDALL,
SMILEY W. LOACH.
